LYMAN J. WILBER, OF BROCKTON, MASSACHUSETTS.

RECEPTACLE-FILLER.

1,226,042.

Specification of Letters Patent. Patented May 15, 1917.

Application filed August 2, 1916. Serial No. 112,709.

To all whom it may concern:

Be it known that I, LYMAN J. WILBER, a citizen of the United States, residing at Brockton, in the county of Plymouth and State of Massachusetts, have invented new and useful Improvements in Receptacle-Fillers, of which the following is a specification.

This invention relates to means for filling barrels, cans, and other receptacles, a conduit being employed having a delivering portion adapted to enter the receptacle and a receiving portion to which the liquid is admitted by suitable means. The conduit 10 is provided with a normally closed valve 15 adapted to be opened and locked in an open position, means being provided for unlocking the valve and permitting it to close when the liquid in the receptacle reaches a 20 suitable height.

The invention has for its object to provide certain improvements in the means for manually opening, automatically locking, and automatically unlocking the valve, 25 and is embodied in the improvements hereinafter described and claimed.

Of the accompanying drawings forming a part of this specification,

Figure 1 represents a side elevation of a 30 receptacle filler embodying my invention applied to a barrel, parts being broken away and parts shown in section.

Fig. 2 represents a top plan view of the filler.

Fig. 3 represents a fragmentary elevation illustrating the locking means when the valve is open.

Fig. 4 represents a view similar to Fig. 3 illustrating the locking means when the 40 liquid has reached a predetermined height in the receptacle.

Fig. 5 represents a section on line 5—5 of Fig. 1.

Figs. 6 and 7 represent fragmentary sectional views showing the valve stem rotated to different position for purposes hereinafter described.

Fig. 8 represents a fragmentary elevation illustrating the action of the auxiliary locking means hereinafter described.

Fig. 9 represents a perspective view of the bracket hereinafter described.

Fig. 10 represents a section on line 10—10 of Fig. 1.

55 The same reference characters indicate the same parts in all the figures.

12 represents the inlet or receiving portion, and 13 the delivering portion of an angular conduit, the receiving portion being adapted by means of a screw thread 14 60 or otherwise to be coupled to a supply pipe, and the delivering portion being adapted to enter an orifice in a barrel 15 or other receptacle. The delivering portion is provided with a valve seat 16 with which co- 65 operates a valve 17 normally closed by suitable means such as the spring 18.

The valve is provided with a stem which includes a lower portion 19 projecting into the delivering portion of the conduit and 70 an upper portion 19^a projecting through a stuffing box 20 on an upper wall of the conduit, the portion 19^a being manually movable to open the valve.

The lower portion 19 constitutes a part of 75 the means for locking the valve open and as here shown is toothed on one side, a plurality of ratchet-shaped teeth 21 being preferably employed.

The complementary part of said locking 80 means is a detent 22 pivoted at 23 to a bracket 24 (Fig. 9) attached by screws 25 to the delivering portion 13. The upper arm of said detent is provided with a shoulder 26 which is normally pressed toward 85 the stem portion 19 by a spring 27, said shoulder being pressed against the stem portion 19 above the toothed portion when the valve is closed, as shown by Fig. 1. When the valve is open, as indicated by dotted 90 lines in Fig. 1, the shoulder 26 engages a stem tooth 21, as shown by Fig. 3, so that the valve is automatically locked in its open position.

Mounted to oscillate on a fixed fulcrum 95 in the delivery portion of the conduit is a bell crank lever comprising a longer arm which includes a float 29 and a shank 29^a, and a shorter detent-displacing arm 30, constituting a trip, said fulcrum being a pin 100 28 engaged with the bracket 24. The float 29 is hollow and hermetically sealed and preferably made of thin sheet metal, the main portion of which is cylindrical, the shank 29^a being suitably secured to one of the heads of the cylinder. When the device is not in use the float 29 is preferably stored in the delivering portion 13 of the conduit, such portion being cut away at one side to form an opening 13^a through which the float 110 may swing outwardly from the delivering portion, as indicated by dotted lines in Fig.

1. The relative arrangement of the float and its shorter arm is such that when the float is stored in the delivering portion the shorter arm 30 is separated from the lower portion 5 of the detent 22. When the float is displaced and swung upwardly the shorter arm or trip 30 gradually approaches the detent 22 and finally abuts against the same to displace it, as indicated by Fig. 4, and thus automatically unlock and permit the closing of the valve.

The operation of the parts thus far described is as follows: The delivering portion 13 is inserted in the receptacle 15, and the 15 valve 17 is manually opened and automatically locked as above described, the detent shoulder 26 being brought into engagement with the tooth 21, as indicated by Fig. 3. The liquid now flows through the conduit 20 into the receptacle. The stream of liquid impinges on the upper head 29^b of the float, said head being inclined relatively to the path of said stream, as shown by Fig. 1, this 25 inclination causing the impact of the descending liquid to partially displace the float outwardly from the delivering portion 13, so that the float is inclined and is in position to be acted on and further displaced by liquid rising in the receptacle. When the 30 rising liquid contacts with the partially displaced float it further displaces the latter until the shorter arm or trip 30 abuts against the detent 22 and displaces the same, as indicated by Fig. 4, the valve being thus automatically unlocked and allowed to close.

The shorter arm 30 is preferably provided with an adjustable member which may be a screw 31 one end of which constitutes the portion which abuts against the detent, said 40 abutting portion being adjustable to regulate the height at which the liquid rises in the receptacle before unlocking the valve.

The valve stem is adapted to be rotated to move its toothed side out of engagement 45 with the detent and thus unlock the valve in case of failure of the unlocking means above described to operate. The upper stem 19^a is provided with a handle 33 by which the stem may be rotated, said handle serving also 50 to indicate the position of the toothed side of the stem. When the stem is turned to the position shown by Fig. 6 its toothed portion is moved away from the detent.

I have provided auxiliary locking means 55 for locking the valve in its closed position, said means being embodied in a locking member 35, which is a notch formed in the detent 22 and a complementary member 36 which is an ear formed on one side of the 60 stem portion 19 and adapted to enter said notch when the stem is turned to the position shown by Figs. 7 and 8, the handle 33 serving to indicate the position of the auxiliary locking member 36.

65 The valve may be opened by means of a

lever 38 fulcrumed at 39 on a bracket 40 attached to the conduit, said lever having a forked end 38^a engaging shoulders on the stem portion 19^a.

The stuffing box 20 and bracket 40 are 70 preferably supported by a cap or cover 41 forming the portion of the conduit wall through which the valve stem passes and detachably secured to the body portion of the conduit. The conduit when used with a 75 barrel may be provided with a flange 42 having bearing screws 43 adapted to rest on the barrel.

Having described my invention, I claim:

1. A receptacle filler comprising a conduit 80 having a delivering portion adapted to enter a receptacle and provided with a valve seat, a normally closed valve coöperating with said seat, means whereby the valve may be manually opened, automatic means for locking the valve in an open position, and a lever supported by and adapted to oscillate on a fixed fulcrum in the delivering portion of the conduit and having a longer arm provided with a float, and a shorter arm, the 85 said float being displaceable by liquid rising in the receptacle, and the shorter arm constituting a trip adapted to render said locking means inoperative and automatically unlock the valve when the float is displaced by 90 the rise of liquid in the receptacle.

2. A receptacle filler comprising a conduit having a delivering portion adapted to enter a receptacle and provided with a valve seat, a normally closed valve coöperating with 100 said seat, means whereby the valve may be manually opened, automatic means for locking the valve in an open position, and a lever supported by and adapted to oscillate on a fixed fulcrum in the delivering portion of the conduit and having a longer arm provided with a float, and a shorter arm, the 105 said float being displaceable by liquid rising in the receptacle, and the shorter arm constituting a trip adapted to render said locking means inoperative and automatically unlock the valve when the float is displaced by 110 the rise of liquid in the receptacle, the shorter arm being provided with an adjustable member whereby the float-displacing 115 rise of liquid may be regulated.

3. A receptacle filler comprising a conduit having a delivering portion adapted to enter a receptacle and provided with a valve seat, a normally closed valve coöperating 120 with said seat, means whereby the valve may be manually opened, automatic means for locking the valve in an open position, and a lever fulcrumed on the delivering portion of the conduit and having a longer arm provided with a float, and a shorter arm, the 125 said float being displaceable by liquid rising in the receptacle, and the shorter arm being arranged to render said locking means inoperative and unlock the valve when the 130

float is displaced by the rise of liquid in the receptacle, the delivering portion of the conduit having an opening in one side permitting the outward displacement of the 5 float, and the float being adapted to normally occupy said delivering portion, and having an inclined head arranged to be displaced outwardly from the delivering portion by a stream of liquid flowing there- 10 through, to prepare the float for further displacement by liquid rising in the receptacle.

4. A receptacle filler comprising a conduit having a delivering portion adapted to enter a receptacle and provided with a valve 15 seat, a normally closed valve coöperating with said seat and provided with a stem composed of an upper portion projecting above the valve through a wall of the conduit and a lower portion projecting below 20 the valve into said delivering portion, said upper portion being manually movable to open the valve, and the lower portion being toothed at one side, a spring-pressed detent adapted to automatically engage a tooth on, 25 said lower portion and lock the valve open, and means operable by a rise of liquid in the receptacle to shift said detent and unlock the valve.

5. A receptacle filler comprising a conduit 30 having a delivering portion adapted to enter a receptacle and provided with a valve seat, a normally closed valve coöperating with said seat and provided with a stem composed of an upper portion projecting 35 above the valve through a wall of the conduit and a lower portion projecting below the valve into said delivering portion, said upper portion being manually movable to open the valve, and the lower portion being toothed at one side, a spring-pressed detent 40 adapted to automatically engage a tooth on said lower portion and lock the valve open, and means operable by a rise of liquid in the receptacle to shift said detent and unlock 45 the valve, the valve stem being rotatable to move its toothed side out of engagement with said detent and unlock the valve.

6. A receptacle filler comprising a conduit having a delivering portion adapted to en-

ter a receptacle and provided with a valve 50 seat, a normally closed valve coöperating with said seat and provided with a stem composed of an upper portion projecting above the valve through a wall of the conduit and a lower portion projecting below 55 the valve into said delivering portion, said upper portion being manually movable to open the valve, and the lower portion being toothed at one side, a spring-pressed detent adapted to automatically engage a tooth on 60 said lower portion and lock the valve open, and means operable by a rise of liquid in the receptacle to shift said detent and unlock the valve, the valve stem being rotatable to move its toothed side out of engagement with 65 said detent and unlock the valve, and provided with a handle serving to rotate the stem and to indicate the position of its toothed side.

7. A receptacle filler comprising a conduit 70 having a delivering portion adapted to enter a receptacle and provided with a valve seat, a normally closed valve coöperating with said seat and provided with a stem composed of an upper portion projecting 75 above the valve through a wall of the conduit and a lower portion projecting below the valve into said delivering portion, said upper portion being manually movable to open the valve, and the lower portion being toothed at one side, a spring-pressed detent adapted to automatically engage a tooth on 80 said lower portion and lock the valve open, and means operable by a rise of liquid in the receptacle to shift said detent and unlock 85 the valve, the valve stem being rotatable, and the lower portion of the stem and the detent being provided with supplemental auxiliary locking members operable by a partial rotation of the stem to lock the valve 90 in its closed position, the upper portion of the stem being provided with a handle serving to rotate the stem and to indicate the position of its auxiliary locking member.

In testimony whereof I have affixed my 95 signature.

LYMAN J. WILBER.
